UNITED STATES PATENT OFFICE.

TULLY SIMPSON, OF ATLANTA, GEORGIA.

CIGARETTE-VENDING DEVICE.

Application filed October 19, 1927. Serial No. 227,078.

This invention is a cigarette vending device, and the object is to provide a relatively simple, practical and efficient device for dispensing cigarettes one at a time upon the insertion of pennies for operating the mechanism.

In the drawing.

Figure 1 is a perspective view of the device in operative position;

10 Figure 2 is a vertical longitudinal section, showing the operating lever depressed;

Figure 3 is a similar view showing the operating lever and cigarette slide elevated as in the process of delivering a cigarette;

15 Figure 4 is a cross section on the line 4—4 in Figure 2;

Figure 5 is a sectional detail of the upper central lid portion of the device taken on the line 5—5 in Figure 3;

20 Figure 6 is an enlarged detail of the coin operated lever locking mechanism.

The device includes a suitable case 1 of a width slightly greater than the length of the cigarettes 2 placed therein, the said case

25 having a medial lever slot 3 in the front end, and a transverse cigarette aperture 4 in the upper side, covered by double doors 5 hinged at 6 to open upwardly as shown. One side as 7 of the case 1 is made detachable as shown

30 and is provided with a lock 8, so that cigarettes may be inserted and coins removed. The upper portion of the interior of the case 1 is partitioned from the lower portion by two transverse V-shaped partitions 9, arranged

35 to slope towards a central opening 10 left between the said partitions for a purpose later pointed out. The opening 10 is vertically aligned with the cigarette aperture 4.

Spaced partitions 11 are supported from

40 the sides of the case 1 transversely of the upper partitioned portion of the case, thus forming a cigarette chute 12 in alignment with the openings 4 and 10. These partitions 11 do not extend quite down to the horizontal or perpendicular partitions 9, thus

45 leaving at each side of the chute 12 cigarette openings 13. Thus two upper cigarette hoppers 14 are formed at each side of the chute 12, with the cigarette openings or slots 13

50 provided through which the cigarettes 2 may be rolled into the lower end of the chute 12. Below the partitions 9 and in alignment with the partitions 11, additional partitions 16 are mounted in spaced relation, thus forming

55 a slide-way 17 aligned with the cigarette chute 12. The partitions 16 are slotted medi-

ally and vertically, as shown at 18 and in alignment with the lever slot 3. A cigarette engaging slide 19 is slidably mounted within the slide-way 17. This slide is substantially 60 of the same width as the length of the cigarettes handled by the device, the upper edge 20 thereof being concaved as shown so as to retain a cigarette 2 resting thereupon, and the lower edge 21 being rounded off as shown 65 so as to better engage the operating lever as will be described.

An operating lever 22 in the form of a flat tube adapted to freely receive and pass a copper penny of the coinage of the United 70

States, or any other desired coin or token, is provided and is passed downwardly at an angle through the aligned slots 3 and 18, below the rounded edge 21 of the slide 19. The lever 22 is pivotally attached at 23 at the lower 75

margin of the slot 3. The slide 19 rests upon the lower and inner end of the lever 22, and when these elements are in their retracted position, the upper concaved edge 20 of the slide will be substantially on a level and in 80

the same plane with the lower webs of the partitions 9. Thus as cigarettes 2 roll out from the hoppers 14 they will roll one at a time upon the concaved edge or end 20 of the slide 19 and will be held there until delivered. 85

This delivery is accomplished by merely bearing down upon the outer end of the lever 22, thus causing the inner end of the lever to play through the slots 18 of the partitions 16 be- 90

neath the slide 19, thereby elevating the slide 90 which pushes the cigarette 2 borne at its upper end, up through the aperture 4. In

this movement the double doors 5 are forced upwardly as shown in Figures 3 and 5. 95

Springs 24 normally hold these doors closed. 100

If desired, a notch or recess 25 may be cut in an upper corner of the slide 19, and then a stop pin 26 mounted at the corresponding end of the aperture 4 and arranged to coact

with the notch 25 in such a way that as the 105 cigarette 2 is forced up by the slide 19, the corner 27 at the recess 25, passing upwardly, will cause an end of the cigarette 2 to be

caught and stopped by the pin 26, thereby tilt- 110

ing the opposite end of the cigarette upwardly ready to the hand of the purchaser. This development is clearly shown in Figure 5. A

lever locking mechanism is provided, consist- 115

ing of a small housing 28 having a counter- weighted trigger 29 pivoted at 30 therein in

such a way that when the lever 22 is depressed the lower point of the trigger 29 will swing

into the open lower end of the lever 22 and so lock that lever against movement. However, upon the deposit of the proper coin, such as the penny 31, through the lateral opening 36 in the upper and outer end of the tubular lever 22, the said coin rolls rapidly down through the lever and impinging sharply against the trigger 29, knocks that trigger free from the open end of the lever 22, therefore 10 by permitting that said lever to be raised, and the slide 19 to be raised, for the purpose of delivering the said cigarette 2, as above described. The housing 28 is provided with an opening 32 facing the lower end of the lever 22, when the latter is depressed, through which opening the said trigger 29 plays. The housing is also provided with a frontal piece 33 immediately above the pivotal point 30 of the trigger 29, and this frontal piece 33 is located just outside of and in parallel relation with the circumference of the imaginary circle defined by the said inner end of the lever 22 in its swiveling movement upon its pivot 23. Thus this piece 33 serves to hold the coin 25 31 within the tubular lever 22 until that lever is elevated above the said housing 28, whereupon the coin will roll down the lever and will fall over back into the bottom of the case 1, as shown in Figure 2. A spring 34 normally holds the lever 22 in its lowered or depressed position as shown in Figure 2, and locked in that position by the trigger 29. A stop pin 35 prevents the trigger 29 from being forced too far outwardly by the impingement 30 of the coin 31.

The lateral coin opening 36 in the upper and outer end of the tubular lever 22 prevents the unauthorized insertion of a wire or the like down through the said lever, for tripping the trigger 29.

It is thought that the use and operation of the device has now been sufficiently shown and illustrated in the foregoing specification, taken in connection with the said drawings. The cigarettes 2 roll one at a time down through the openings 13 upon the concaved upper end of the slide 19, by which they are elevated to the hand of the user, upon his depositing a coin through the lever 22, and operating the lever as stated.

While I have here shown a preferred embodiment of my invention, it is understood that I may vary from the same in minor details of construction, within the scope of the appended claim.

I claim:

In a coin operated dispensing device, the combination of a vertically arranged element slidably mounted, a hollow lever downwardly inclined and loosely engaging the said vertically arranged slidable element, and a trigger movably mounted at and in alignment with the lower end of the said hollow lever, the said trigger being adapted to normally engage the lower end of the lever and to be released therefrom by the impingement of a coin rolling down through said lever.

In testimony whereof I affix my signature.

TULLY SIMPSON.
